(57) **CLAIM**

The ornamental design for a beverage container lid, as shown and described.

DESCRIPTION

FIG. 1 is a top perspective view of a beverage container lid showing my new design;

FIG. 2 is a front view thereof;

FIG. 3 is a rear view thereof;

FIG. 4 is a right side view thereof;

FIG. 5, is a left side view thereof;

FIG. 6 is a top view of thereof; and,

FIG. 7 is a bottom view thereof.

The broken line and the space within the broken line in FIG. 7 depict portions of the beverage container lid that form no part of the claimed design.

1 Claim, 3 Drawing Sheets
